UNITED STATES PATENT OFFICE.

EARLE WAYNE TOWNSEND, OF CENTERVILLE, ALABAMA.

GIN.

1,174,204.

Specification of Letters Patent. Patented Mar. 7, 1916.

Application filed May 17, 1915. Serial No. 28,712.

To all whom it may concern:

Be it known that I, EARLE W. TOWNSEND, a citizen of the United States, residing at Centerville, in the county of Bibb and State 5 of Alabama, have invented certain new and useful Improvements in Gins, of which the following is a specification, reference being had to the accompanying drawings.

This invention relates to certain improvements in gins and has relation more particularly to an attachment therefor; and the object of the invention is to provide an attachment of this general character having novel and improved means whereby the 15 saw may be cleaned in substantially an automatic manner and without the necessity of interrupting the operation of the gin.

The invention consists in the details of construction and in the combination and arrangement of the several parts of my improved gin whereby certain important advantages are attained and the device is rendered simpler, less expensive and otherwise more convenient and advantageous for 25 use, all as will be hereinafter more fully set forth.

The novel features of the invention will be carefully defined in the appended claim.

In order that my invention may be the 30 better understood, I will now proceed to describe the same with reference to the accompanying drawings, wherein—

Figure 1 is a view in side elevation, illustrating a gin having a cleaning attachment 35 constructed in accordance with an embodiment of my invention applied thereto; Fig. 2 is a view similar to Fig. 1, illustrating my invention adjusted into an inoperative position; Fig. 3 is a view, partly in elevation 40 and partly in section, of my device as herein embodied; Fig. 4 is a view in end elevation of the cleaning cylinder herein included; Fig. 5 is a fragmentary view in top plan of said cleaning cylinder; and Fig. 6 is a view 45 in perspective, detached, of one of the detachable blocks coacting with the cleaning cylinder.

As disclosed in the accompanying drawings, 1 denotes the stand or frame of the gin 50 and 2 a shaft rotatably supported thereby and to which are affixed the circular saws 3 and with which is adapted to coact in a well known manner, the brush 4 carried by the shaft 5 disposed rearwardly of the shaft 2.

The stand or frame 1 at a point substantially directly below the shaft 2 has opera-

tively engaged therewith a rock shaft 6 arranged in parallelism with the shaft 2 and extending upwardly from said shaft 6 are the rock arms 7, on the free extremities of 60 which is rotatably supported the shaft 8, a projected extremity of said shaft 8 being provided with a drum 9 around which is disposed a belt 10 also directed around a pulley 11 affixed to the shaft 5, hereinbefore 65 referred to.

One of the rock arms 7 is provided with an angularly disposed arm 12 having its free extremity provided with a roller 14 adapted to bear against the belt 10 whereby sufficient 70 tension is created upon the belt to cause the rotation of the shaft 8 when the rock arms are moved upwardly under the influence of the operating lever 15 suitably affixed to an extremity of the shaft 6. 75

Fixed to the shaft 8 between the arms 7 is a drum or cylinder 16 of a length to underlie all of the saws 3 and secured longitudinally of said drum or cylinder in predetermined radially separated relation are the 80 blocks 17 of compressible material, preferably rubber. It is to be observed that each of the blocks 17 are detachably engaged with the drum or cylinder 16 through the medium of the headed screw 18, although I wish to 85 be particularly understood that any other means for securing the block 17 in operative position may be employed which will operate with convenience and facility.

It is to be observed that the drum or cylinder 16 rotates in a direction opposite to the shaft 2 and that when the rock arms 7 have been elevated in substantially a vertical position, the teeth of the saws 3 are adapted to pass between adjacent blocks 17 95 whereby the throats of said teeth are thoroughly cleaned, and in practice I have found this device to be of especial advantage when the cotton is damp as the blocks 17 impart a pinching action upon the cotton. In order 100 to facilitate the effectiveness of my device, it is to be observed that the opposed faces of the blocks 17 are oppositely beveled to afford entrance openings, as indicated at 19, and that the lower rear portions of the 105 opposed faces of the blocks are downwardly and oppositely beveled, as at 20, to afford exit openings for the escape of any matter that may accumulate between the blocks. It will also be readily appreciated that by having the opposed faces of the blocks 17 beveled, as at 19 and 20, a more effective en- 110

gagement of the blocks with the saws 3 is assured.

From the foregoing description, it is thought to be obvious that a gin constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

20 In combination with a cotton gin, and a

saw therein; a shaft mounted below the saw and capable of movement relatively thereto, compressible blocks carried by the shaft, the opposed faces of said blocks being in contact, the peripheral portion of the saw being adapted to pass between said blocks when the shaft is moved toward the saw, the opposed faces of the blocks being forwardly and oppositely beveled, whereby the forward portions of the opposed faces are separated the lower marginal portions of the rear of the opposed faces of the blocks being also beveled in a direction angular to the first named bevel to afford an exit opening.

In testimony whereof I hereunto affix my signature in the presence of two witnesses.

EARLE WAYNE TOWNSEND.

Witnesses:

H. M. SMITHERMAN,
M. G. CREWS.
